(57) CLAIM

The ornamental design for a card for a card game, as shown and described.

DESCRIPTION

FIG. 1 is a front view of a first embodiment of a card, showing my new invention; and

FIG. 2 is a front view of a second embodiment thereof; and, FIG. 3 is a front view of another card of the present invention that includes an image of a cow in the center zone of the card.

The card of the present invention is substantially planar and no claim is made to the thickness of the card or the back side of the card.

The broken line showing is included for the purpose of illustrating portions of the “article” and forms no part of the claimed design.

1 Claim, 3 Drawing Sheets
